UNITED STATES PATENT OFFICE

153,215

DESIGN FOR A CANDY BOX OR THE LIKE

George N. Hange, Chicago, Ill.

Application March 22, 1946, Serial No. 127,768

Term of patent 7 years

(Cl. D58—13)

To all whom it may concern:

Be it known that I, George N. Hange, a citizen of the United States and residing in the city of Chicago, in the county of Cook and State of Illinois, has invented a new, original, and ornamental Design for a Candy Box or the like, of which the following is the specification, reference being had to the accompanying drawings, forming a part thereof.

Fig. 1 is a top perspective view of a candy box showing my new design, and

Fig. 2 is a top plan view thereof.

I claim:

The ornamental design for a candy box or the like, substantially as shown.

G. N. HANGE.
